UNITED STATES PATENT OFFICE.

GEORGE W. WARNER, OF FREEPORT, ILLINOIS.

DOOR-CHECK.

SPECIFICATION forming part of Letters Patent No. 634,596, dated October 10, 1899.

Application filed January 30, 1899. Serial No. 703,775. (No model.)

To all whom it may concern:

Be it known that I, GEORGE W. WARNER, of Freeport, in the county of Stephenson and State of Illinois, have invented certain new and useful Improvements in Door-Checks; and I do hereby declare that the following is a full, clear, and exact description thereof, reference being had to the accompanying drawings, and to the letters of reference marked thereon, which form a part of this specification.

This invention relates to an improvement in pneumatic door-checks such as are used for doors having closing-springs.

15 The invention consists in the matters hereinafter set forth, and more particularly pointed out in the appended claim.

In the accompanying drawings, illustrating my invention, Figure 1 is a view in plan 20 section of a device embodying my invention, showing a door and door-frame, the door being illustrated in its closed position. Fig. 2 is a similar view illustrating the door in its open position. Fig. 3 is a detail section taken 25 on line 3 3 of Fig. 1. Fig. 4 is a view in side elevation of the parts when in the position shown in Fig. 1. Fig. 5 is a detail section through the inner end of the air-cylinder of the device, taken on the line 5 5 of Fig. 4. 30 Fig. 6 is a detail view showing the screw-plug by which the size of the air-exit of the said cylinder is regulated.

As illustrated in said drawings, A indicates the door jamb or frame, and B a door hinged 35 thereto. The door will commonly be provided with a closing-spring of some kind, the same being herein shown as provided with spring-hinges, one of which is shown at B'.

C designates an air-cylinder; D, a piston 40 therein; D', a piston-rod rigidly attached to the piston; E, a lever which is pivoted to the door and connected with the piston, and F a link connected at one end with the said lever and pivoted at its opposite end to the inner 45 face of the door-jamb A. The said cylinder C is pivoted at one end to the door-jamb by any suitable pivotal connection allowing it to swing in a horizontal plane, that herein shown consisting of laterally-projecting trunnions 50 c c on the end of the cylinder, which trun-

nions are engaged with the bearing lugs of brackets G G, attached to the door-jamb. Said cylinder C is closed at its end nearest the door-jamb by an end wall C', Fig. 5, which end wall is provided with a small passage for the 55 escape of air from the cylinder. Admission of air to the cylinder is afforded by the construction of the packing d of the piston D, which packing consists of a flexible disk of leather or like material attached centrally to 60 the inner face of the piston and so arranged as to permit the passage of air past it when the piston is drawn outwardly, but to hold the air when the piston is thrust inwardly.

The lever E is connected by a pivot h to a 65 bracket H, which is secured in any suitable manner to the inner face of the door near the hinged edge thereof. At its opposite or outer end said lever is connected by a pivot e with the free end of the link F, which link F is 70 connected at its opposite end by a pivot f with a bracket I, attached to the inner face of the door-jamb. The pivotal connection of said link F with the door-jamb is arranged at a point between the inner end of the cylinder 75 and the hinged edge of the door. For convenience of construction the brackets G G, to which the cylinder is hinged, and the bracket I, with which the link is connected, are formed integral with a base casting or plate 80 J, which is secured by screws or in any other suitable manner to the inner vertical face of the door-jamb.

The piston-rod D' is connected with the lever E by a pivot d', located between the extremity of the arm which is connected with the link F and its end which is attached to the door, and said arm E is bent at a point near the said pivot d', so that its laterally-projecting part or arm E' between the pivot 85 d' and the end of the link F has transverse relation to the cylinder and the link when the door is closed and will occupy an oblique position with respect to and will be nearly in alinement with said parts when the door is 90 open. The shape of said lever E or the angle of the arm E' thereof with respect to the main part of the lever is such, moreover, that when the door is closed, as seen in Fig. 1, the piston D will be held at the extreme 95 100

inward movement of the cylinder and the pivot d' will be much nearer the door than the outer end of the link F, so that said link will extend across the cylinder or stand in an oblique position with reference thereto. Moreover, said link F is bent or deflected downwardly at a point near its outer end, so as to bring its main part or portion below the level of the cylinder and avoid contact of the lever with the cylinder in the movement of the parts.

As a result of the bent form of the lever E described when the door is in its open position, as shown in Fig. 2, the piston will be drawn outwardly in the cylinder, said cylinder and link F at such time being in positions approximately at right angles to those originally occupied by them, so that when by the opening of the door the parts are placed in the position described the piston will be moved a distance nearly equal to the distance between the pivot of the cylinder and the pivot f of the link F plus the distance between the pivot d' , joining the piston-rod with the lever E and the pivot e at the outer end of said lever.

Obviously a main feature of the device is involved in the separation of the piston-rod pivot d' and the pivot e , connecting the link with the actuating-lever E, so that on opening the door the piston moves outwardly and upon closing the door the piston moves inwardly in the cylinder. This operation would also obtain if the pivot joining the link to the jamb were placed in vertical alinement with the pivot of the cylinder, and the connection of said parts with the lever E remained as shown in the drawings, it being obvious that in such case the piston would move out on opening the door and into the cylinder on closing the door. It will also be apparent that if the connection of the piston-rod with the end of the link were at the point where the link joins the lever E instead of in the place indicated in the drawings the result would be practically the same as before; but in that case the piston would be moved to an extent due to the distance apart of the cylinder-pivot and link-pivot only. In other words, the feature of lateral separation of the pivotal connections of the link and cylinder with the actuating-lever and the door-jamb affords means for moving the piston in the cylinder, and while such lateral separation at either the jamb or actuating-lever alone will produce this result the combination of the two features affords maximum movement and accomplishes the best result. Moreover, the lateral separation of the link-pivot from the cylinder-pivot provides the greatest degree of motion in the piston when the door is approaching its open position, but will be insufficient to check the door at the closing-point if relied upon alone. The lateral separation of the link-pivot f and

piston-rod pivot d' on the actuating-lever, however, gives motion to the piston at once on first opening the door and can be depended on by itself to accomplish the result; but such a construction would not always be desirable, because giving too great a projection of the outer end of the lever from the inner face of the door in order to get a long enough arm to give the required motion. The best results, therefore, are obtained by lateral separation of the pivots at both ends of the cylinder and link.

The opening at the inner end of the cylinder for the escape of air from the cylinder is formed by means of a screw-threaded aperture c' in the end wall C, in which aperture is inserted a screw-stud c^2 , having an oblique flattened face c^3 , Figs. 5 and 6, by which the size of the exit-opening may be varied through endwise movement of the screw in said aperture c' . This construction affords a simple means of regulating the escape of air from the cylinder and enables the rapidity of its outflow to be varied in accordance with the pressure of the spring and other considerations.

As shown in the accompanying drawings, the outwardly-bent part or laterally-extended arm E' of the actuating-lever E is approximately parallel with the inner face of the jamb or at right angles with the face of the door when the door is closed. The arm may, however, be located at a somewhat different angle with respect to these parts, the only essential requirement being that when the door is opened the said actuating-lever turning on its connection with the link as a fulcrum should throw the piston to the outer end of the cylinder and when the door is closed it should throw the piston to the inner end of the cylinder. It will also be noted that the attachment of the cylinder to the jamb and the piston-rod to the actuating-lever is not essential, as substantially the same result would be arrived at by the equivalent construction, in which these parts are reversed and the cylinder pivoted to the actuating-lever, while the piston-rod is pivoted to the door-jamb. This reversal of the construction is therefore intended to be included in the matters covered by the appended claim.

I claim as my invention—

A door-check comprising a cylinder pivotally connected with the inner face of the door-jamb at a distance from the door, an actuating-lever pivoted to the door near the hinged edge thereof, said lever being bent to form an arm which projects laterally from the door, a piston in the cylinder provided with a piston-rod which is pivotally connected with the said lever at the inner end of said laterally-projecting arm, and a link pivoted at its inner end to the inner face of the door-jamb near the door and between the pivot of the cylinder and the said door, and at its outer

end to the outer end of said laterally-projecting arm of the actuating-lever, at a distance from the pivot connecting said cylinder with said arm, said link standing in crossed relation to the cylinder when the door is closed.

5 In testimony that I claim the foregoing as my invention I affix my signature, in presence

of two witnesses, this 18th day of January, A. D. 1899.

GEORGE W. WARNER.
